UNITED STATES PATENT OFFICE.

AMOS WILLIAM RUSH, OF GRAND RAPIDS, MICHIGAN, ASSIGNOR TO NORTH-WESTERN EXPANDED METAL COMPANY, OF CHICAGO, ILLINOIS, A CORPORATION OF ILLINOIS.

EXPANDED-METAL-SPlicing DEVICE.

No. 857,307.

Specification of Letters Patent.

Patented June 18, 1907.

Application filed December 19, 1906. Serial No. 348,608.

To all whom it may concern:

Be it known that I, AMOS WILLIAM RUSH, a citizen of the United States, residing in Grand Rapids, in the county of Kent and State of Michigan, have invented a new and useful Improvement in Expanded-Metal-Splicing Devices, of which the following is a specification.

It is frequently necessary in the use of expanded metal in buildings and elsewhere, to attach sheets of metal together at their ends or side edges, and the object of the present invention is to provide a splicing device whereby the sheets may be securely united at their edges and the fastening be of a nature which will be permanent and which will not be objectionable by reason of its size or shape.

My improved splice piece is adapted to receive within itself strands of the united sheets, and for this purpose, it is made in two parts, each having a recess for the metal, and after being positioned, the parts are riveted together.

The nature of my improvement is fully shown in the accompanying drawing, in which

Figure 1 shows the device in use and as uniting sheets of the metal. Fig. 2 is a section on the line 2—2 of Fig. 1. Fig. 3 is an enlarged plan of one of the parts of the splice with a strand of the expanded metal positioned in it. Fig. 4 is a view similar to Fig. 3 showing the ends of one of the sheets positioned in the splice. Fig. 5 is a section of the splice at right angles to the section given in Fig. 2. Fig. 6 is a section on the line 6—6 of Fig. 5.

Referring to said drawing, 10, 11 and 12 represent portions of different sheets of expanded metal united by my invention. As shown, the splice consists of two plates 13 and 14, each having formed therein a groove 15 into which a strand of the expanded metal may be inserted, as best shown at Fig. 3. One of the plates receives a strand of one of the sheets to be united and the other splice

plate receives a strand of the other sheet. One of the plates is provided with riveting pins 16 at each end, and the other plate is provided with openings to receive such pins. When put together, the rivets will project through the openings and are then hammered down flush therewith, as will be understood from Figs. 5 and 6. As shown in Fig. 2, the splice is employed to unite the side edges of two sheets. It may, however, be used to unite the ends of the sheets and is so shown in the case of the splice at the right of Fig. 1, the same grooves being adapted to receive the uncut end of two strands of the sheet, as will be better understood from Fig. 4.

The device is extremely simple, is easily applied, forms a very secure attachment of sheets one to another and is inexpensive.

The walls of the grooves resist the drawing apart of the sheets when their side edges are united as well as any longitudinal movement of either sheet relative to the other, and where the ends of two sheets are united as in Fig. 4, the triangular shoulders at the ends of the coupling enter and engage the angles of the sheets and effectually hold them with the uncut butts of the sheets in contact as plainly shown.

I claim:

1. The splice for uniting sheets of expanded metal, consisting of grooved plates adapted to receive the edges or ends of the metal and to be united by riveting the shoulders formed by the grooves resisting both lateral and longitudinal separation of the sheets united by the splice.

2. The two part splice for uniting sheets of expanded metal, the parts of the splice having recesses or pockets shaped so as to adapt them to receive and hold either the ends or the side edges of the sheets and also adapted to be riveted together upon the metal.

AMOS WILLIAM RUSH.
